Inventor

United States Patent Office.

F. W. BROCKSIEPER, OF NEW HAVEN, CONNECTICUT, ASSIGNOR TO
SARGENT & CO., OF SAME PLACE.

Design No. 3,692, dated October 5, 1869.

DESIGN FOR A MATCH-SAFE.

The Schedule referred to in these Letters Patent and making part of the same.

To all whom it may concern:

Be it known that I, F. W. BROCKSIEPER, of New Haven, in the county of New Haven, and State of Connecticut, have invented a new Design for Match-Safe; and I do hereby declare the following, when taken in connection with the accompanying drawing, to be a full, clear, and exact description of the same, and which said drawing constitutes part of this specification, and represents a front view.

The invention relates to a design for two receptacles for matches, or one for the matches and the other for the stumps, arranged so as to be hung against the wall; and

The design consists in two oak leaves from a single stem, combined, and upon each leaf a large acorn forms the receptacle for the matches, all as fully shown in the accompanying photographic illustration.

I claim as my invention—

The design for match-safe, as herein described and shown.

F. W. BROCKSIEPER.
